Mr. T. H. H.

UNITED STATES PATENT OFFICE

ROBERT G. JENNINGS, OF ELMIRA, NEW YORK, ASSIGNOR TO THE R. G. JENNINGS
YARN CLEANING MACHINE CO. INC., OF ELMIRA, NEW YORK, A CORPORATION OF
NEW YORK

KNITTING-MACHINE SPOT-DYEING APPARATUS

Application filed July 17, 1928. Serial No. 293,474.

My invention relates to a spot-dyeing appliance for use with knitting machines and is here illustrated in connection with a body machine of the circular type, though its use 5 is not confined to that particular type of machine.

It is an object of my invention to provide a spot-dyeing means which shall operate in such a manner as not to injure the needles, 10 as has heretofore been done by applying a dye to the yarn before it passes down to the needles. This causes rusting of the needles and if the yarn is fine it results in tender 15 yarns and holes in the fabric. By applying the dye to the fabric after knitting the 20 dampness makes no difference. Alcohol is commonly used as a solvent for the dye in spot-dyeing of the unknitted yarn, because of its penetrating and its quick-drying 25 properties, but water can be used as a solvent with the device of my invention, in place of a portion of the alcohol, or may replace it altogether in use if the cloth is exposed to drying conditions for some time after spot-dyeing, as is usually the case.

Another object of my invention is to save 30 in the use of dye and particularly in the use of alcohol which ordinarily forms an ingredient thereof, this economy being due to 35 the fact that the dye is applied to the outside of the cloth so that the full effect of the dye is apparent, whereas when dye is applied to the yarn that part of the yarn showing at the inside of the cloth is dyed 40 but without any benefit as there is no reason why the spots should appear at the inside of the garment. On the other hand it is advantageous to have the inner side of the cloth white as the dye sometimes comes off on the skin of the wearer, as many persons prefer garments undyed on the inner side.

Another object of the invention is to apply 45 the dye in such a manner that it will not be thrown off, as occurs when the dye is applied to the yarn which is whirling around with great speed and consequently with a development of high centrifugal force. By applying the dye to the slowly moving cloth 50 this action is avoided.

Still another object is to save the cost of re-winding, as heretofore practice in spot-dyeing yarn, and also the cost of floor space for winders, upkeep of winders, etc.

Referring to the drawings, which are made 55 a part of this application, and in which similar reference characters indicate similar parts:—

Fig. 1 is an elevation of my machine viewed from the front; 60

Fig. 2 is a detail vertical section on a larger scale, the section being taken on line 2—2 of Fig. 3;

Fig. 3 is a plan of parts shown in Fig. 2; 65

Fig. 4 is a transverse section of the machine on line 4—4 of Fig. 1;

Fig. 5 is a detail plan of a spot-dyeing appliance;

Fig. 6 is a side elevation corresponding to Fig. 5; 70

Fig. 7 is an elevation of parts shown in Fig. 5, viewed from the left; and

Fig. 8 is a sectional view on line 8—8 of Fig. 7.

In the drawings, reference character 10 75 indicates the head of a rib knitting machine of the type known as a body machine, said machine having a series of cylinder needles 11 and a series of dial needles 12. The machine generally is of known type, having a take-up 13 for the fabric which passes around a pair of stretching rings 14, 14 on its way to the take-up. A shaft 15 drives the cam-ring 14 in conventional manner, the shaft carrying a fast pulley 16 and a 80 loose pulley 17 driven by a belt controlled by a belt-shifter 18 with a handle 19, whereby it may be moved manually. A belt 20 drives the take-up by means of pulleys 21 and 22.

An annulus 23 is held in place about the stretching rings 14, 14 by means of legs 24 mounted on base-plate 25 and a cylindrical guide 26 extends upward from annulus 23. The guide 26 and a roller bearing 27 on annulus 23 provide means for supporting and guiding a rotary support 28 for the spot-dyeing devices with which my invention is particularly concerned. The support 28 rotates with the cam-ring and dial cam cap, 90 100

though not necessarily at the same speed or in the same direction, but I do not limit myself to such a construction as relative movement only is necessary and the principle 5 may be embodied even in a straight machine.

The support 28 is driven by a belt 29 passing over a pulley 30 on a shaft 31 driven by a pinion 32 meshing with the usual crown-gear (not shown) secured to the cam-ring 10 and driven by gearing connecting it to shaft 15. The belt passes from pulley 30 to a guide pulley 32, then about support 28, then about another guide pulley (not shown) and then back to pulley 30.

15 On the support there are a suitable number of color-applying devices, here shown as constructed for the application of dye in liquid form to the fabric, and each consisting of a bracket 33 pivoted at 34 on the upwardly-extending flange of support 28. Springs 34' tend to move the brackets on their pivots so as to hold the rotary members or friction gears 35 in contact with the fabric and also to hold nozzles 36 close to 20 or in contact with the fabric. To facilitate the rotation of the friction gears 35 the circumference thereof is knurled or roughened as shown clearly in Fig. 6. The nozzles are attached, preferably by screw-threads, to 25 blocks 37 (Figs. 5 to 7) having a longitudinal passage leading to the port of the nozzle, from a short tube 38 also connected to the block preferably by screw-threads. A pipe 39 connects the short tube 38 to a supply 30 tank 40 which may supply dye to several or all the nozzles. As here shown two tanks supply the various nozzles.

A valve 41 (Fig. 7) is held in place in block 37 by a screw 42, this valve having 40 a passage adapted to register with the passage of block 37. An arm 43 is secured to the top of the valve by a screw 44 or in any other convenient manner. Another arm 45 on the valve is moved by a spring 46 in a 45 direction for normally closing the valve, the movement of arm 45 being limited by a pin 46'.

The gear 35 has two pins 48 projecting upward into the plane of movement of arm 50 43 (Fig. 6) and it will be evident that the pins will strike the arm 43 as the gear is rotated in the operation of the machine, to thereby open the valve 41 and permit the dye 55 to be ejected against the cloth by reason of the pressure of the fluid in tank 40. This pressure may be augmented in various ways, if desired, as by forcing air under pressure into the tank. Preferably threaded holes are 60 formed in the gear, whereby the number and location of the pins 48 may be varied according to the pattern desired.

It will be apparent also that the design or pattern desired to be produced on the finished fabric may be varied also by locating 65

the spot dyeing appliance at different distances apart on the supporting rings.

It is desirable that the application of color should cease on stoppage of the machine and for this end I have provided means to remove the nozzles 36 from the fabric when the machine stops, and means for also cutting off the flow of dye. Such means comprises a ring 49 mounted on support 28 for rotation therewith, the ring being attached to the support by one or more springs 50 (Fig. 3).

Sleeves 51 are mounted on posts on support 28 so as to contact with the inner face of ring 49, thus providing anti-friction guiding means for the ring, and overhanging flanges 52 (Fig. 2) are provided on said sleeves for holding down the ring 49. Bent fingers 53 on the ring engage over radial pins 54 mounted on valves 55 pivoted on blocks 37, each valve having a passage normally registering with the passage in a block 37. The valves are held in place by screws 56 (Figs. 3 and 5). A brake 57 (Figs. 1 and 4) is slidably supported on a bracket 58 and is forced toward ring 49 by a spring 59. A lever 60 is connected at its lower end to brake 57 and its upper end is located in the path of a rod 61 connected to the shifter 19 for movement therewith in a direction to remove the brake from the ring 49 when the belt is shifted from the loose to the fast pulley in starting the machine.

Operation: In the operation of my device it will be seen that the gears 35 rotate as the machine is driven, the circumference of the friction gears being in contact with the rotating fabric, as shown, with the result that whenever a pin 48 strikes a finger 43 the corresponding valve 41 will be opened and, as this opens the passage from the tank 40 to the nozzle 36 it follows that coloring matter will be ejected from the nozzles due to the hydrostatic pressure in the tank or to other pressure, as above explained.

The valve is open only during the time it takes for the pin 48 to pass and release the finger 43 when the spring 46 closes the valve again and the dye will therefore be applied in a machine of the character illustrated several times by each device during a rotation of the machine, the sequence being adapted to be varied as above described or in other ways.

When the machine is stopped, as by a stop motion controlled by failure of yarn, by a press-off or otherwise, the power is cut off by shifting the belt from the fast pulley to the loose pulley. As the belt shifter moves for this purpose the rod 61 moves out of the way of lever 60 and permits the spring 59 to apply the brake 57 to the ring 49, the parts being so proportioned that the brake will be applied before the machine has ceased its rotation.

130

As a result of this the bent fingers 53 will stop and by their engagement will cause movement of pins 54, thereby rotating valves 55 into closed position and cutting off the flow of the dye. At the same time the flat faces at 62 on the valves 55 will engage with the outer wall of the upper flange of support 28 and will move the bracket 33, on which the gear 35 is supported, about its pivot 34 against the tension of spring 34' to carry the nozzle 36 away from the fabric.

In this way the flow of dye is cut off and application of such dye as remains in the nozzle and the passage in the block is also prevented. When the belt is shifted back to the fast pulley the brake will be removed and the spring or springs 50 will carry the ring 28 back to its normal position thereby re-opening the valves 55.

It will be obvious to those skilled in the art that various modifications may be made in my device without departing from the spirit of the invention, and therefore I do not limit myself to what is shown in the drawings and described in the specification, but only as indicated in the appended claims.

What I claim as new, and desire to secure by Letters Patent of the United States, is:—

- 30 1. In a knitting machine, stopping means, a support having movement relatively to the cloth in a direction transverse to the wales thereof, a color-applying device mounted on said support, means for causing said device to apply coloring matter to the cloth being knitted after passing the knitting point during the operation of said knitting machine, and means actuated by the stopping means for removing said device from the fabric when the machine stops.
- 40 2. In a knitting machine, stopping means, a support having movement relatively to the cloth in a direction transverse to the wales thereof, means mounted on said support for applying a liquid to said cloth, means for operating said liquid applying means while the knitting machine is running, and means actuated by the stopping means for preventing further application of color by said color applying means when the machine stops.

3. In a knitting machine, stopping means, a support having movement relatively to the cloth in a direction transverse to the wales thereof, means mounted on said support for applying a liquid to said cloth, means for operating said liquid applying means at intervals during the knitting of a course of stitches, and means actuated by the stopping means for preventing further application of color by said color applying means when the machine stops.

4. In a circular knitting machine, means for knitting a fabric, a support on said machine spaced from the knitting means and rotatable relatively to the fabric, stopping

means, a series of color-applying devices arranged in spaced relation on said support, means for operating said devices during the knitting of a course, and means actuated by the stopping means for preventing operation of said devices between stoppage and re-starting of the machine.

5. In a knitting machine, a support having movement relatively to the cloth in a direction transverse to the wales thereof, a nozzle having an opening adjacent the fabric, means for supplying liquid coloring matter to said nozzle, and means for intermittently shutting off the supply of coloring matter.

6. In a circular knitting machine, means for knitting a fabric, a support on said machine spaced from the knitting means and rotatable relatively to the fabric, a series of color-applying devices arranged in spaced relation on said support, each of said devices including a nozzle adjacent the fabric, and means for ejecting coloring material through said nozzles at intervals during the knitting of a course.

7. In a circular knitting machine, means for knitting a fabric, a support on said machine spaced from the knitting means and rotatable relatively to the fabric, a series of color-applying devices arranged in spaced relation on said support, each of said devices including a nozzle adjacent the fabric, means for ejecting coloring material through said nozzles at intervals during the knitting of a course, and means for preventing further flow from said nozzles after stoppage of the machine.

8. In a circular knitting machine, means for knitting a fabric, a support on said machine spaced from the knitting means and rotatable relatively to the fabric, a series of color-applying devices arranged in spaced relation on said support, each of said devices including a nozzle adjacent the fabric, means for ejecting coloring material through said nozzles at intervals during the knitting of a course, and means for moving the nozzles away from the fabric on stoppage of the machine.

9. In a circular knitting machine, means for knitting a fabric, a support on said machine spaced from the knitting means and rotatable relatively to the fabric, a series of color-applying devices arranged in spaced relation on said support, each of said devices including a nozzle adjacent the fabric, means for ejecting coloring material through said nozzles at intervals during the knitting of a course, means for moving the nozzles away from the fabric on stoppage of the machine, and means for automatically returning the nozzles to position on re-starting the machine.

10. In a circular knitting machine, means for knitting a fabric, a support on said ma-

chine spaced from the knitting means and rotatable relatively to the fabric, a series of color-applying devices arranged in spaced relation on said support, each of said devices including a nozzle adjacent the fabric, a passage leading to the nozzle, means for supplying liquid coloring matter under pressure to said nozzle through said passage, a valve in the passage, and means for intermittently opening said valve.

10. 11. In a circular knitting machine, means for knitting a fabric, a support on said machine spaced from the knitting means and rotatable relatively to the fabric, a series of color-applying devices arranged in spaced relation on said support, each of said devices including a nozzle adjacent the fabric, a passage leading to the nozzle, means for supplying liquid coloring matter under pressure to said nozzle through said passage, a valve in the passage, means for intermittently opening said valve, a second valve in each passage, said last-named valve being normally open, and means for closing each 25 of said last-named valves on stoppage of the machine.

12. In a circular knitting machine, means for knitting a fabric, a support on said machine spaced from the knitting means and 30 rotatable relatively to the fabric, a series of color-applying devices arranged in spaced relation on said support, each of said devices including a nozzle adjacent the fabric, a passage leading to the nozzle, means for supplying liquid coloring matter under pressure to said nozzle through said passage, a valve in the passage, means for intermittently opening said valve, a second valve in each passage, said last-named valve being normally open, means for closing each of said 40 last-named valves on stoppage, and means for automatically re-opening said valves on re-starting the machine.

13. In a circular knitting machine, means 45 for knitting a fabric, a support on said machine spaced from the knitting means and rotatable relatively to the fabric, a series of color-applying devices arranged in spaced relation on said support, each of said devices including a nozzle adjacent the fabric, a passage leading to the nozzle, means for supplying liquid coloring matter under pressure to said nozzle through said passage, a valve in the passage, a gear operated by the 55 rotation of the machine, and means operated by said gear for opening the valve intermittently.

14. In a circular knitting machine, means 60 for knitting a fabric, a support on said machine spaced from the knitting means and rotatable relatively to the fabric, a series of color-applying devices arranged in spaced relation on said support, each of said devices including a nozzle adjacent the fabric, a 65 passage leading to the nozzle, means for sup-

plying liquid coloring matter under pressure to said nozzle through said passage, a valve in the passage, a gear operated by the rotation of the machine, a finger on the valve, a pin on the gear adapted to engage said finger to open the valve, and means to close the valve on release of said finger by said pin.

15. In a circular knitting machine, means for knitting a fabric, a support on said machine spaced from the knitting means and 75 rotatable relatively to the fabric, a series of color-applying devices arranged in spaced relation on said support, each of said devices including a nozzle adjacent the fabric, means for ejecting coloring material through said 80 nozzles at intervals during the knitting of a course, means for preventing further flow from said nozzles after stoppage of the machine including an element extending circumferentially of the machine, means normally holding it in one position, means to change its position on stoppage of the machine, and connections from said element to render said color-applying devices inoperative 85 on such change of position.

16. In a circular knitting machine, means for knitting a fabric, a support on said machine spaced from the knitting means and rotatable relatively to the fabric, a series of color-applying devices arranged in spaced 95 relation on said support, each of said devices including a nozzle adjacent the fabric, means for ejecting coloring material through said nozzles at intervals during the knitting of a course, an element extending circumferentially of the machine, connections from said element to said color-applying devices, and means to operate said element on stoppage 100 of the machine for moving the nozzles away from the fabric.

17. In a circular knitting machine, means for knitting a fabric, a support on said machine spaced from the knitting means and rotatable relatively to the fabric, a series of color-applying devices arranged in spaced 110 relation on said support, each of said devices including a nozzle adjacent the fabric, means for ejecting coloring material through said nozzles at intervals during the knitting of a course, an element extending circumferentially of the machine, connections from said element to said color-applying devices, means to operate said element on stoppage 115 of the machine for moving the nozzles away from the cloth, and means for automatically returning said element on re-starting the machine thereby returning said devices to operative position adjacent the fabric.

18. In a circular knitting machine, a stationary needle bed, a rotary needle cam carrier, a series of devices for applying color to the fabric rotating with said carrier, a ring rotating with said carrier, a brake automatically applied to said ring on stoppage 125 of the machine, and connections from said 130

ring for inhibiting further operation of the color-applying devices when the brake is applied to the ring.

19. In a circular knitting machine, a stationary needle bed, a rotary needle cam carrier, a series of devices for applying color to the fabric rotating with said carrier, each having a nozzle close to the cloth, a ring rotating with said carrier, a brake automatically applied to said ring on stoppage of the machine, and connections from the ring for moving said nozzles away from the fabric on stoppage of the machine.

20. In a circular knitting machine, a stationary needle bed, a rotary needle cam carrier, a series of devices for applying color to the fabric rotating with said carrier, a ring rotating with said carrier, a brake automatically applied to said ring on stoppage of the machine, connections from said ring for inhibiting further operation of the color-applying devices when the brake is applied to the ring, and means for automatically restoring said devices to operation on again starting the machine.

21. In a circular knitting machine, a stationary needle bed, a rotary needle cam carrier, a series of devices for applying color to the fabric rotating with said carrier, a ring rotating with said carrier, a brake automatically applied to said ring on stoppage of the machine, connections from said ring for inhibiting further operation of the color-applying devices when the brake is applied to the ring, and means serving to return said ring to normal position on re-starting the machine.

22. A color-applying device for knitting machines comprising a nozzle, having an opening adjacent the fabric, a passage leading to said nozzle, a valve in the passage, a gear, and connections from said gear to said valve for operating the same.

23. A color-applying device for knitting machines comprising a nozzle, having an opening adjacent the fabric, a passage leading to said nozzle, a valve in the passage, a gear, connections from said gear to said valve for opening the passage, and means for closing the valve automatically after being operated by said gear.

24. In a knitting machine stopping means, a color-applying device mounted thereon, and means for causing said device to apply coloring matter to the knitted cloth after the knitting point during the operation of the knitting machine, and means actuated by the stopping means for removing the color applying portion of said device from the fabric when the machine stops.

25. In a knitting machine stopping means, a color-applying device mounted thereon, and means for causing said device to apply coloring matter to the knitted cloth after the knitting point during the operation of

the knitting machine, and means actuated by the stopping means for preventing further application of coloring matter by said color-applying device when the operation of the knitting machine ceases.

26. A color applying device for knitting machines comprising a nozzle having an opening adjacent the fabric, a passage leading to said nozzle, a valve in the passage, a gear, and means on said gear for periodically operating said valve.

27. A color applying device for knitting machines, comprising a nozzle having an opening adjacent the fabric, a passage leading to said nozzle, a valve in the passage, a gear, and removable means on said gear for actuating the valve, said gear being provided with means for receiving said removable means in different positions on the gear whereby the design or pattern being applied to the fabric may be varied.

In testimony whereof I hereunto affix my signature.

ROBERT G. JENNINGS.
